FIG. 1 is a top plan view of a sewing machine carrying case or similar article embodying my new design;

FIG. 2 is one end elevational view thereof;

FIG. 3 is the other end elevational view thereof;

FIG. 4 is a front elevational view thereof;

FIG. 5 is a rear elevational view thereof;

FIG. 6 is a bottom plan view thereof; and

FIG. 7 is a perspective view thereof.

The characteristic features of my new design reside in the specific shape of the top including a raised rib spaced intermediate the front and rear walls and extending from each end wall toward a handle of the same configuration in combination with the front and rear walls which intersect the end walls to provide interior facing portions of the end walls which taper from a wide portion on the top

toward a narrow portion which merges into a horizontally disposed slightly recessed line forming a border adjacent the base of the unit.

I claim:

The ornamental design for a sewing machine carrying case or similar article, substantially as shown and described.
